(57) **CLAIM**

The ornamental designs for a bottle, as shown and described.

DESCRIPTION

FIG. 1 is a top perspective view of a bottle showing my new design, the bottle having an opening with an unclaimed thread;

FIG. 2 is a bottom perspective view thereof;

FIG. 3 is a front elevation view thereof, the right side, left side and rear elevation views being identical, excluding the unclaimed thread detail;

FIG. 4 is a top plan view thereof; and,

FIG. 5 is a bottom plan view thereof.

The broken lines in the drawings showing the thread applied to the pour spout of the bottle illustrates the portions of the design that form no part of the claim.
